File History of U.S. Appl. No. 29/514,538, filed Jan. 13, 2015, priority date Dec. 4, 2009, entitled Hub for Motorized Wheel.

(Continued)

Primary Examiner — Stacia A Cadmus(74) *Attorney, Agent, or Firm* — GTC Law Group PC & Affiliates(57) **CLAIM**

The ornamental design for a single speed motorized wheel hub, as shown and described.

DESCRIPTION

FIG. 1 is a perspective view of the left, drive side, of the single speed motorized wheel hub attached to a vehicle, with various portions including a gear shown in broken lines; FIG. 2 is a left, drive side, plan view of the single speed motorized wheel hub;

FIG. 3 is a front view of the single speed motorized wheel hub;

FIG. 4 is a right, non-drive, side plan view of the single speed motorized wheel hub; and,

FIG. 5 is a perspective view of the right, non-drive, side of the single speed motorized wheel hub attached to the vehicle.

In the drawings, the broken lines depict environmental subject matter only and form no part of the claimed design.

1 Claim, 5 Drawing Sheets(56)
